(57) **CLAIM**

I claim the ornamental design for a bandage scissors, as shown and described.

DESCRIPTION

FIG. 1 is a perspective view of a bandage scissors, showing my new design;

FIG. 2 is a right-side elevational view of FIG. 1;

FIG. 3 is a left-side elevational view of FIG. 1;

FIG. 4 is a top plan view of FIG. 1;

FIG. 5 is a bottom plan view of FIG. 1;

FIG. 6 is a front elevational view of FIG. 1; and,

FIG. 7 is a rear elevational view of FIG. 1.

1 Claim, 2 Drawing Sheets

FIG. 1

FIG. 2
